UNITED STATES PATENT OFFICE.

THOMAS RIGEY, OF DUMFRIES, SCOTLAND, AND NILS TESTRUP, OF LONDON, ENGLAND, ASSIGNORS, BY MESNE ASSIGNMENTS, TO WETCARBONIZING LIMITED, OF LONDON, ENGLAND.

CLEANING TUBULAR AND OTHER VESSELS.

1,106,161.

Specification of Letters Patent.

Patented Aug. 4, 1914.

Application filed December 6, 1911. Serial No. 664,265.

To all whom it may concern:

Be it known that we, THOMAS RIGEY, a subject of the King of Great Britain and Ireland, and residing at Station Hotel, 5 Dumfries, Scotland, and NILS TESTRUP, a subject of the King of Great Britain and Ireland, and residing at 6 Broad Street Place, London, E. C., England, have invented certain new and useful Improvements in 10 the Cleaning of Tubular and other Vessels, of which the following is a specification.

This invention relates to the removal of deposited matter from or the prevention of deposit in vessels employed in the treatment 15 or handling of matters liable to produce deposits. An example of such an apparatus is the apparatus which has been proposed for wet carbonizing peat.

This invention is more particularly applicable to apparatus such as is described in 20 the pending application filed by one of us, and bearing Serial No. 613099. It has been observed that in the inside of the inner tubes of apparatus of the latter kind, the peat material is liable during the heating operation 25 to deposit at certain points, which deposit rapidly accumulates, and frequently leads to choking, local overheating, and may eventually lead to rupture of the tube, and generally speaking, is a source of low efficiency.

This invention has for its object to provide means particularly adapted to remove this defect, but applicable also to any appliance where similar difficulty may arise.

According to this invention, the deposit, if any is formed, is dislodged, or the prevention of deposition is obtained by occasionally causing, when necessary, an abnormally rapid and preferably sudden motion 35 of the fluid within the vessel. This may be caused to occur periodically, and if desired, automatically, and in the preferred form effected by establishing communication between a suitable part of the apparatus and a 40 space at a considerably lower pressure than that which exists within the same.

The accompanying diagrammatic drawings show the invention applied in one way, by way of example, to a wet carbonizing apparatus, such as is shown and described in 50 the application above referred to; only such

parts thereof being indicated in these drawings as are necessary to the understanding of the present invention.

The form of the invention shown is one in 55 which the desired effect is obtained by providing a cap capable of application to the end of the inner carbonizing tube, and formed with an outlet suitably controlled to allow of placing the inside of the tube in 60 communication with a space at a lower pressure than that existing in the tube, means being at the same time provided for effecting the application of the cap to the tube automatically for any predetermined period and 65 at any predetermined time.

Figure 1 shows a partial elevation in section of an apparatus as above referred to, corresponding plan and end elevations being shown in Figs. 2 and 3.

From each peat inlet header *a* extends a plurality of peat carbonizing elements composed of outer tubes *e* with concentric open ended inner tubes *g*, which extend through the header *a*, passing through stuffing boxes 70 *m* in the same, and enter the peat outlet headers *b*, passing also through stuffing boxes *m'* in the headers *b*. Within the headers *b* are provided a plurality of caps *r*, adapted when suitably placed closely to fit 75 the extremities of the tubes *g*. Each cap is carried by a tube *d*, which opens into it, and which passes out through a stuffing box *n*, from the chamber *b*. This tube extends into and through a third header *c*, passing 80 into and out of the latter through suitable stuffing boxes *o* and *o'*, and being closed at its farther extremity by a suitable screw plug *q*. It is adapted to be capable of sliding longitudinally through the stuffing 85 boxes, and has a long bearing in the wall of the header *c*, at *s*. The tube *d* has at that part of it which is within the latter long bearing when the tube and adapter are fully retracted from the tubes *g*, an orifice *p* 90 formed by cutting away a part of its periphery. Each tube is provided at the part between the headers *c* and *d* with suitably disposed collars *u* and *v*, between which the extremities of arms *h*, mounted on shafts *l*, 100 and adapted to be reciprocated thereby, these shafts being connected by arms *f*; to

links w , which are connected to the piston rod x of a hydraulic, pneumatic or other suitable cylinder.

The operation of the device is as follows:—In any predetermined sequence, as determined by the method of connection to the operating means, and for any desired period and at any desired time, as determined by the admission of operating fluid to the cylinder y , each cap r is, during the operation of the carbonizer, caused to fit over the end of the corresponding tube g by the action of the arm h co-acting with the collars u and v causing the tube d of the cap to be pushed on to the same. This action, however, causes the orifice p to over-run the long bearing s , and therefore puts the inside of the tube g in which the peat is contained under high pressure into communication through the cap and tube d and orifice p with the inside of the header c , which is maintained at a lower, *e. g.*, atmospheric pressure. This leads to a very sudden rush of peat from and through the tube g , and this violent motion causes any deposit which has formed to be loosened and dislodged. The period during which this communication is maintained may be determined by the tendency which the material under treatment has to form deposits, but is relatively short, the return motion of the piston rod x causing the tube d to be retracted, and the communication to be interrupted. The headers c are connected to the storage tank of the installation, or to any other suitable reservoir to prevent waste of peat. Any suitable means other than that shown may of course be adopted for causing the reciprocation of the caps.

It is to be observed that the number of tubes which are at the same time submitted to the cleansing treatment should be limited so as not unduly to interrupt the flow of peat through the apparatus, and therefore to interrupt the working conditions of the apparatus as a whole. By effecting cleaning at very frequent intervals, such as say every ten minutes, for each tube, the formation of any substantial deposit may be altogether prevented, and a smaller period of opening and a smaller amount of material ejected than in removing deposit which has accumulated during a relatively long period. The screw caps q allow of access for cleaning the tubes d , without dismantling the apparatus.

The application of cleaning means according to the present invention preventing the formation of deposit while resulting in an increase in the life of the apparatus and the period during which the same may safely be employed without overhauling, also leads to an increase in the heat efficiency of the apparatus which may be such as to allow of substantial reduction of the heat-

ing area of the same by virtue of the increase in heat conducting capacity of the tube walls both in the heated zone and in the zone where regeneration of the heat occurs.

Having now described our invention, what we claim as new and desire to secure by Letters Patent is:—

1. Apparatus for heating peat, comprising in combination a plurality of peat heating elements, a vessel receiving the peat therefrom, another vessel at a lower pressure than that existing within the heating elements, and means by which the latter vessel can be placed in communication with the heating elements while simultaneously disconnecting the latter from the receiving vessel in order thereby to cause dislodgment of peat deposited within the heating elements.

2. Apparatus for heating peat, comprising in combination a plurality of double concentric tubes through which the peat is continuously passed while being heated, a vessel receiving the peat therefrom, another vessel at a lower pressure than that existing within the tubes, and means by which the lower pressure vessel can be placed in communication with any of the double concentric tubes while simultaneously causing the latter to be disconnected from the receiving vessel in order thereby to effect removal of peat deposited within the concentric tubes.

3. Apparatus for heating peat, comprising in combination a plurality of double concentric heating tubes, a vessel in which the outlet ends of said tubes are situated, another vessel at a lower pressure than that existing within said tubes, and means by which the outlet ends of the tubes are utilized to enable the lower pressure vessel to be placed in communication with the interior of the tubes and at the same time be disconnected from the receiving vessel for the purpose of removing peat deposited within the heating tubes.

4. Apparatus for heating peat, comprising in combination a plurality of double concentric heating tubes, a vessel in which the outlet ends of said tubes are situated, another vessel at a lower pressure than that existing within said tubes, a cap adapted to be placed on the outlet end of each tube, a tubular member extending from within each cap to the lower pressure vessel in such a manner that when a cap is placed on the outlet end of any of the heating tubes communication is established between the latter and the lower pressure vessel, and simultaneously disestablished between said tubes and the vessel containing the outlet end thereof, for the purposes set forth.

5. Apparatus for the treatment of fluid matters, comprising in combination an open-ended tubular element, a vessel in proximity to said apparatus at a lower pressure than

that within the tubular element, a cap adapted to be applied to the open end of said element, a tube extending from within said cap and passing through said vessel, said tube having a port near the end remote from the cap, and a bearing within which said tube can be slid longitudinally within said vessel to apply the cap to the open end of the tubular element and at the same time 5 uncover the port in the tube, thereby placing the tubular element and the vessel in communication.

In testimony whereof we have signed our names to this specification in the presence of two subscribing witnesses.
